UNITED STATES PATENT OFFICE.

JOSEPH THOMPSON PARKER, OF WASHINGTON, DISTRICT OF COLUMBIA.

ARMORED AEROPLANE.

1,189,616.

Specification of Letters Patent.

Patented July 4, 1916.

Application filed February 11, 1916. Serial No. 77,687.

To all whom it may concern:

Be it known that I, JOSEPH THOMPSON PARKER, a citizen of the United States of America, and a resident of Washington, District of Columbia, have invented certain new and useful Improvements in Armored Aeroplanes, of which the following is a full and clear specification.

The object of this invention is to provide an aeroplane with a gun or fire-arm so arranged and mounted that it will fire axially through the propeller shaft, this shaft being provided with an axial passage throughout its length for this purpose, and the gun being rigidly mounted with respect to the axial line of the propeller shaft, so that the gun will be aimed by the aviator by simply aiming the aeroplane at the target, as more fully hereinafter set forth.

In the drawing is represented a view, partly in side elevation and partly in section, of so much of an aeroplane as is necessary to illustrate my invention.

In the drawings, *a* designates the propeller shaft, which may be driven in any suitable or usual manner from the motor mounted on the machine. This shaft is axially bored throughout its length. At the rear end of the propeller shaft is mounted rigidly on the frame of the aeroplane a gun *b*, which may be any of the usual types of automatic guns. This gun may be so placed as to be operable by the aviator or it may be so located as to be conveniently operated by a gunner carried for the purpose. If a gun of the type automatically operated by gas pressure or by recoil be employed, it may be conveniently operated by the aviator himself, as in this type of gun it is simply necessary to press a trigger to continue the fire. The rear end of the propeller shaft is bored out to a sufficiently large diameter to receive the end *c* of the gun barrel. The end of the gun barrel will nicely fit this enlarged part of the bore of the shaft, so that the gun barrel will have a firm rest on the rear end of the shaft. The main part of the bore through the shaft is the same diameter as the bore of the gun barrel, so that it forms in effect a continuation of the gun barrel. In this way I utilize the propeller shaft as an extension of the gun barrel, and this will enable me to shorten the gun barrel to the extent of the length of the propeller shaft. Of course, the bore in the shaft may be rifled, if desired, but I believe that, by rea-

son of the fact that the shaft is being rigidly rotated during the firing action, very little, if any, rifling will be required, since the rotation of the shaft will impart a rotative movement to the projectile. This feature of my invention may be applied to ordnance of the smaller types, whether used on an aeroplane or not, and I therefore do not limit myself, so far as this feature is concerned, to the application of the invention to an aeroplane; that is to say, I believe myself to be the first to conceive of the idea of rotating a part of the gun barrel during firing action, to thereby spin the projectile and thus eliminate rifling or greatly reduce it as to depth and pitch.

It will be understood, of course, that in all cases that part of the gun barrel which is attached to the gun will not rotate, but will in all cases be rigidly supported on or adjacent the end of the propeller shaft. I show the gun barrel entering but a short distance into the propeller shaft, but it will be understood that it may be extended farther thereinto or even entirely through the propeller shaft. Just to the extent, however, that the barrel is extended into the propeller shaft, I of course lose the advantage of the propeller shaft as a gun barrel. It will be observed that when the gun is thus rigidly mounted behind the propeller shaft with its gun barrel axially in alinement with the axial center of the propeller shaft, the aviator may aim the gun by simply maneuvering the aeroplane, so that the gunner, if an additional operator be carried on the machine, will have nothing to do but operate the gun. I believe that by thus putting the matter of aiming the gun completely in the hands of the aviator, a much more effective attack on an enemy can be made than where the gun is aimed by another person. Where a gun is aimed by a person other than the aviator, a great many shots must necessarily go wild, in view of the impossibility of effective coöperation between the gunner and the aviator. With my invention, no coöperation is necessary, as the aviator does all the aiming. If the cartridges or shells be arranged in the magazine of the gun so that at intervals a smoke-emitting, target-finding shell of the well known type be discharged, it will be seen that the aviator will be greatly assisted in maneuvering his machine to bring the fire upon the target.

It will be understood that my invention is not restricted to details of construction, and I have therefore made no attempt to illustrate details in my drawing.

5 The trigger of gun could be so designed as to be operated by hand, foot, knee or any part of the body of the operator.

Having thus described my invention, what I claim is:

- 10 1. The combination with an aeroplane whose propeller shaft is axially hollow, of a gun mounted rigidly on the aeroplane and having its barrel coupled to the rear end of the shaft and axially in line with the passage through the shaft, the passage through the shaft being large enough in diameter to permit free passage of bullets but not large enough to permit shifting of the gun barrel independently of the shaft in aiming, so
- 15 20 that the gun is aimed by maneuvering the aeroplane and not by adjusting the gun independently of the aeroplane.
- 25 2. The combination with an aeroplane whose propeller shaft is axially hollow, of a gun rigidly mounted on the aeroplane and having its barrel axially in line with the passage of the shaft, the forward end of the gun barrel entering the shaft and having a relatively rotatable bearing thereon,

so that the gun is aimed by maneuvering the 30 aeroplane and not by adjusting the gun independently of the aeroplane, axial alignment being insured by the engagement of the forward end of the gun barrel with the propeller shaft.

35 3. The combination with an aeroplane whose propeller shaft is axially hollow, of a gun rigidly mounted on the aeroplane and having its barrel axially in line with the passage of the shaft, the forward end of the 40 gun barrel entering the shaft part way thereof, the bore in the shaft beyond the end of the barrel being of the same diameter as the bore in the gun barrel, so that the shaft forms in effect an extension of the gun 45 barrel.

4. The combination with an aeroplane whose propeller shaft is axially hollow, of a gun rigidly mounted on the aeroplane and having its barrel axially in line with the 50 passage through the shaft, the bore in the shaft beyond the end of the barrel being of the same diameter as the bore in the gun barrel, so that the shaft forms in effect a rotatable extension of the gun barrel.

55 In testimony whereof I hereunto affix my signature.

JOSEPH THOMPSON PARKER.
